(74) *Attorney, Agent, or Firm* — Calfee, Halter & Griswold LLP

(57) **CLAIM**

The ornamental design for a handle as shown and described.

DESCRIPTION

FIG. 1 is a front, left perspective view of a handle of the new design;

FIG. 2 is a rear, right perspective view of the handle of FIG. 1;

FIG. 3 is a front elevational view of the handle of FIG. 1, the rear elevational view being a mirror image thereof;

FIG. 4 is a left side elevational view of the handle of FIG. 1;

FIG. 5 is a right side elevational view of the handle of FIG. 1;

FIG. 6 is a top plan view of the handle of FIG. 1; and, FIG. 7 is a bottom plan view of the handle of FIG. 1.

The broken lines are included for the purpose of illustrating portions of the article and form no part of the claimed design.

1 Claim, 3 Drawing Sheets
